LONGITUDINALLY STEPPED CATHEDRAL BOAT

Richard C. Cole, 100 Madeira Ave., Coral Gables, Fla.

Filed Feb. 8, 1965, Ser. No. 83,737

Term of patent 14 years

(Cl. D71—1)

FIG. 3

FIG. 5

FIG. 4

FIGURE 1 is a side elevational view of a cathedral boat showing my new design.

FIGURE 2 is a top plan view.

FIGURE 3 is a bottom plan view.

FIGURES 4 and 5 are rear and front elevational views respectively.

I claim:

The ornamental design for a longitudinally stepped cathedral boat, substantially as shown.
